[57] CLAIM

The ornamental design for windchimes, as shown and described.

DESCRIPTION

FIG. 1 is a perspective view of a windchime showing my new design; with the undisclosure sides being the same in appearance;

FIG. 2 is an enlarged top perspective view of the upper suspension element shown separately for clarity of illustration only;

FIG. 3 is an enlarged perspective view of the clapper element shown separately for clarity of illustration only; and

FIG. 4 is an enlarged side elevational of the feather element and a fragmentary portion of the support cord.

FIG. 3

FIG. 4

FIG. 2

FIG. 1
